Primary Examiner — Rashida Johnson(74) *Attorney, Agent, or Firm* — QuickPatents; Kevin Prince(57) **CLAIM**

I claim the ornamental design for jeans, as shown and described.

DESCRIPTION

FIG. 1 is a perspective view of jeans, showing my new design;
 FIG. 2 is a front elevational view of FIG. 1;
 FIG. 3 is a rear elevational view of FIG. 1;
 FIG. 4 is a right-side elevational view of FIG. 1;
 FIG. 5 is a left-side elevational view of FIG. 1;
 FIG. 6 is a top plan view of FIG. 1; and,
 FIG. 7 is a bottom plan view thereof.

The broken lines showing a person in FIG. 1 depict environmental matter and form no part of the claimed design. The remaining broken lines represent stitching, and are part of the claimed design.
